ABSTRACT OF THE DISCLOSURE

Certain tetrahydro-s-triazin-2[1H]-ones having the formula

wherein R₁, R₂, and R₃ are various organic radicals hereinafter defined are useful as hypoglycemic agents.

RELATED CASES

This application is a continuation-in-part of copending Ser. No. 571,697, filed Aug. 11, 1966, now abandoned.

DESCRIPTION OF THE INVENTION

General

This invention relates to novel substituted triazones, particularly to tetrahydro-s-triazin-2[1H]-ones, and to their use as hypoglycemic agents.

The compounds of this invention have the formula:

where:

R₁ is

wherein X is hydrogen, alkyl of 1-4 carbon atoms, alkoxy of 1-4 carbon atoms, alkylthio of 1-4 carbon atoms, alkanoyl of 2-4 carbon atoms, trifluoromethyl, chlorine, fluorine, bromine or amino and Y is hydrogen or alkyl of 1-4 carbon atoms;

R₂ is alkyl of 2-10 carbon atoms, cycloalkyl of 3-8 ring carbon atoms, cycloalkenyl of 3-8 ring carbon atoms, bicycloalkyl of 7-10 ring carbon atoms, bicycloalkenyl of 7-10 ring carbon atoms, tricycloalkyl of 8-11 ring carbon atoms, tricycloalkenyl of 8-10 ring carbon atoms, or

wherein n is 0, 1, or 2;

R₃ can be the same as R₂ or hydrogen.

2

The terms "cycloalkyl," "cycloalkenyl," "bicycloalkyl," "bicycloalkenyl," "tricycloalkyl," and "tricycloalkenyl" as used herein are intended to include the respective group optionally substituted on the ring or on the ring portion of the group with substituents which will not interfere with the desired hypoglycemic activity of the compounds of the invention. Illustrative of such optional substituents, but not necessarily all inclusive, are alkyl or alkoxy groups containing one or two carbon atoms.

In accordance with the present invention, I have discovered that compounds of the above class are effective as hypoglycemic agents. These compounds are orally active antidiabetic agents useful for lowering blood sugar content in warm-blooded animals as evidence by in vivo tests in rats and dogs. The hypoglycemic activity of these compounds can be readily demonstrated by animal tests which are known to correlate with antidiabetic activity in man, such as those reviewed by Auguste Lobatieres in chapter 37 "Hypoglycemic Agents," vol. II, Academic Press, London (1964).

The preferred compounds because of their outstanding hypoglycemic activity include

where Z is methyl, ethyl, acetyl, chlorine or bromine; R₄ and R₅ are the same or different and are alkyl of 3-6 carbon atoms, cycloalkyl of 5-7 ring carbon atoms, bicycloalkyl or bicycloalkenyl of 7 or 8 ring carbon atoms, tricycloalkyl of 10 ring carbon atoms.

Methods of preparation

The novel compounds of this invention can be made by one or more of the following three methods.

The first process involves the reaction between an arylsulfonyl isocyanate and a substituted methylene amine. Although some substituted methylene amines exist as the cyclic trimers, namely, hexahydro-s-triazines, and are properly named as such, the exact form of the substituted methylene amine has no bearing on this process. The chemical reaction is represented by the following chemical equation:

where R₁ and R₂ have the same meaning as defined above.

The reaction may be accomplished in the absence of solvent or in the presence of an inert anhydrous solvent

such as dioxane, toluene or acetone. The reaction occurs readily at temperatures between 10° and 100° C.

Certain of the compounds of this invention can also be made by a second process, which uses a 1-arylsulfonyl-3-alkylurea, formaldehyde and an acid catalyst. This reaction is described by the following chemical equation:

where R_1 and R_2 have the same meaning as defined above.

The reaction of a substituted sulfonyl urea is effected in solution of a suitable anhydrous solvent at temperatures of 20°–50° C. with either paraformaldehyde or s-trioxane as the source of formaldehyde. Suitable solvents for the reaction are dioxane, dimethylformamide or dimethylsulfoxide. An acid catalyst is required for the reaction. Sulfuric acid and p-toluenesulfonic acid, for example, are suitable catalysts. The water formed in the reaction should be removed to achieve highest yields. Azeotropic distillation using benzene or contacting the reaction with a suitable drying agent such as magnesium sulfate can be used effectively.

The third method for the preparation of the novel compounds of this invention involves the reaction of an amine salt of a 1-arylsulfonyl-3-alkylurea with formaldehyde in the presence of an acidic catalyst. The chemical reaction is represented by the following chemical equation:

where R_1 , R_2 and R_3 have the same meaning as defined above. Actually, when R_2 and R_3 for the reactant in the

above equation are different, the product triazinone will be present as a mixture of our compounds as follows:

15 20 If desired, these compounds can be separated by fractional crystallization, chromatography, or other known methods which will be obvious to those skilled in the art.

This reaction is performed in the same manner as that 25 described in the second method given above, except that an amine salt of the 1-arylsulfonyl-3-alkylurea is used instead of the urea.

A better understanding of the invention will be gained 30 from the following examples which are for the purpose of illustrating the various features thereof.

EXAMPLE 1

Preparation of 1-(p-toluenesulfonyl)-3,5-di-(n-butyl) tetrahydro-s-triazin-2[1H]-one-first method

35 To a well stirred solution of 17.0 parts by weight of 1,3,5-tri-(n-butyl)hexahydro-s-triazine and 87 parts by weight of anhydrous toluene is added, dropwise, 19.7 parts by weight of p-toluenesulfonylisocyanate. After the initial heat evolution, the solution is maintained at 60° C. for six hours. The solvent is removed by stripping under reduced pressure and the residue is recrystallized to give essentially pure 1-(p-toluenesulfonyl)-3,5 - di - (n-butyl)tetrahydro-s-triazin-2[1H]-one.

The following tetrahydro-s-triazin-2[1H]-ones of this 45 invention can be made similarly by substituting the appropriate amount of the following hexahydro-s-triazine reagents or methylene amine reagents and sulfonylisocyanate reagents for 1,3,5-tri-(n-butyl)hexahydro-s-triazine and p-toluenesulfonylisocyanate employed as re-50 actants hereinabove.

Example	Hexahydro-s-triazine or N-methylene amine	Sulfonyl isocyanate	Tetrahydro-s-triazin-2[1H]-one
2.....	1,3,5 trimethylhexahydro s triazine.....	p Toluenesulfonyl isocyanate.....	1 (p-toluenesulfonyl) 3,5 dimethyl tetrahydro-s-triazin 2[1H]-one.
3.....	1,3,5 triethylhexahydro s-triazine.....	do.....	1-(p-toluenesulfonyl)-3,5-diethyl-tetrahydro-s-triazin-2[1H]-one.
4.....	1,3,5-tri(n-propyl)hexahydro-s-triazine.....	do.....	1-(p-toluenesulfonyl)-3,5-di(n-propyl)-tetrahydro-s-triazin-2[1H]-one.
5.....	1,3,5-triisopropylhexahydro-s-triazine.....	do.....	1-(p-toluenesulfonyl)-3,5-diisopropyl-tetrahydro-s-triazin-2[1H]-one.
6.....	1,3,5-tri(sec-butyl)hexahydro-s-triazine.....	do.....	1-(p-toluenesulfonyl)-3,5-di(sec-butyl)-tetrahydro-s-triazin-2[1H]-one.
7.....	1,3,5-triisobutylhexahydro-s-triazine.....	do.....	1-(p-toluenesulfonyl)-3,5-diisobutyl-tetrahydro-s-triazin-2[1H]-one.
8.....	N-methylene-t-butylamine.....	do.....	1-(p-toluenesulfonyl)-3,5-di (t-butyl)-tetrahydro-s-triazin-2[1H]-one.
9.....	1,3,5-tri(n-pentyl)hexahydro-s-triazine.....	do.....	1-(p-toluenesulfonyl)-3,5-di(n-pentyl)-tetrahydro-s-triazin-2[1H]-one.
10.....	1,3,5-triisopentylhexahydro-s-triazine.....	do.....	1-(p-toluenesulfonyl)-3,5-diisopentyl-tetrahydro-s-triazin-2[1H]-one.
11.....	1,3,5-tris(1-methyl butyl)hexahydro-s-triazine.....	do.....	1-(p-toluenesulfonyl)-3,5-bis(1-methyl butyl)tetrahydro-s-triazin-2[1H]-one.
12.....	N-methylene-neopentylamine.....	do.....	1-(p-toluenesulfonyl)-3,5-di(neopentyl)-tetrahydro-s-triazin-2[1H]-one.
13.....	1,3,5-tris(1,2-dimethylpropyl)-hexahydro-s-triazine.....	do.....	1-(p-toluenesulfonyl)-3,5-bis(1,2-dimethylpropyl)tetrahydro-s-triazin-2[1H]-one.
14.....	1,3,5-tris(1,3-dimethylbutyl)-hexahydro-s-triazine.....	do.....	1-(p-toluenesulfonyl)-3,5-bis(1,3-dimethylbutyl)tetrahydro-s-triazin-2[1H]-one.
15.....	1,3,5-tris(2,2,4-trimethylpentyl)-hexahydro-s-triazine.....	do.....	1-(p-toluenesulfonyl)-3,5-bis(2,2,4-trimethylpentyl)tetrahydro-s-triazin-2[1H]-one.
16.....	1,3,5-tri(n-decyl)-hexahydro-s-triazine.....	do.....	1-(p-toluenesulfonyl)-3,5-di(n-decyl)-tetrahydro-s-triazin-2[1H]-one.
17.....	1,3,5-tricyclopropylhexahydro-s-triazine.....	do.....	1-(p-toluenesulfonyl)-3,5-dicyclopropyl-tetrahydro-s-triazin-2[1H]-one.

Example	Hexahydro-s-triazine or N-methylene amine	Sulfonyl isocyanate	Tetrahydro-s-triazin-2[1H]-one
18	1,3,5-tricyclobutylhexahydro-s-triazine.	do	1-(p-toluenesulfonyl)-3,5-dicyclobutyl-tetrahydro-s-triazin-2[1H]-one.
19	1,3,5-tricyclopentylhexahydro-s-triazine.	do	1-(p-toluenesulfonyl)-3,5-dicyclopentyl-tetrahydro-s-triazin-2[1H]-one.
20	1,3,5-tricyclohexylhexahydro-s-triazine.	do	1-(p-toluenesulfonyl)-3,5-dicyclohexyl-tetrahydro-s-triazin-2[1H]-one.
21	1,3,5-tricycloheptylhexahydro-s-triazine.	do	1-(p-toluenesulfonyl)-3,5-dicycloheptyl-tetrahydro-s-triazin-2[1H]-one.
22	1,3,5-tricyclooctylhexahydro-s-triazine.	do	1-(p-toluenesulfonyl)-3,5-dicyclooctyl-tetrahydro-s-triazin-2[1H]-one.
23	1,3,5-tris(4-methylcyclohexyl)-hexahydro-s-triazine.	do	1-(p-toluenesulfonyl)-3,5-bis(4-methylcyclohexyl)-tetrahydro-s-triazin-2[1H]-one.
24	1,3,5-tri(2-cyclohexenyl)-hexahydro-s-triazine.	do	1-(p-toluenesulfonyl)-3,5-di(2-cyclohexenyl)-tetrahydro-s-triazin-2[1H]-one.
25	1,3,5-tri(3-cyclopentenyl)-hexahydro-s-triazine.	do	1-(p-toluenesulfonyl)-3,5-di(3-cyclopentenyl)-tetrahydro-s-triazin-2[1H]-one.
26	1,3,5-tri(2-cyclooctenyl)-hexahydro-s-triazine.	do	1-(p-toluenesulfonyl)-3,5-di(2-cyclooctenyl)-tetrahydro-s-triazin-2[1H]-one.
27	N-methylene-2-norbornyl amine.	do	1-(p-toluenesulfonyl)-3,5-di(2-norbornyl)-tetrahydro-s-triazin-2[1H]-one.
28	N-methylene-2-bicyclo[2.2.2]-octyl amine.	do	1-(p-toluenesulfonyl)-3,5-di(2-bicyclo[2.2.2]octyl)-tetrahydro-s-triazin-2[1H]-one.
29	N-methylene-2-bicyclo[4.4.0]decyl amine.	do	1-(p-toluenesulfonyl)-3,5-di(2-bicyclo[4.4.0]decyl)-tetrahydro-s-triazin-2[1H]-one.
30	N-methylene-2-bicyclo[2.2.1]-hept-5-enyl amine.	do	1-(p-toluenesulfonyl)-3,5-di(2-bicyclo[2.2.1]-hept-5-enyl)-tetrahydro-s-triazin-2[1H]-one.
31	N-methylene-2-bicyclo[2.2.2]-oct-5-enyl amine	do	1-(p-toluenesulfonyl)-3,5-di(2-bicyclo[2.2.2]-oct-5-enyl)-tetrahydro-s-triazin-2[1H]-one.
32	N-methylene-2-bicyclo[4.2.2]-dec-3-enyl amine	do	1-(p-toluenesulfonyl)-3,5-di(2-bicyclo[4.2.2]-dec-3-enyl)-tetrahydro-s-triazin-2[1H]-one.
33	N-methylene-1-amino-5-methyltricyclo[3.2.2.0 ^{2,4}]nonane	do	1-(p-toluenesulfonyl)-3,5-di(5-methyl-tricyclo[3.2.2.0 ^{2,4}]non-1-yl)-tetrahydro-s-triazin-2[1H]-one.
34	N-methylene-1-adamantyl amine	do	1-(p-toluenesulfonyl)-3,5-di(1-adamantyl)-tetrahydro-s-triazin-2[1H]-one.
35	N-methylene-2-adamantyl amine	do	1-(p-toluenesulfonyl)-3,5-di(2-adamantyl)-tetrahydro-s-triazin-2[1H]-one.
36	N-methylene-6-aminotricyclo[3.2.1.0 ^{2,4}]octane.	do	1-(p-toluenesulfonyl)-3,5-di(6-tricyclo[3.2.1.0 ^{2,4}]octyl)-tetrahydro-s-triazin-2[1H]-one.
37	1,3,5-tri(n-butyl)hexahydro-s-triazine.	Benzenesulfonyl isocyanate.	1-benzenesulfonyl-3,5-di(n-butyl)-tetrahydro-s-triazin-2[1H]-one.
38	1,3,5-tri(n-propyl)hexahydro-s-triazine.	p-chlorobenzenesulfonyl isocyanate.	1-(p-chlorobenzenesulfonyl)-3,5-di(n-propyl)-tetrahydro-s-triazin-2[1H]-one.
39	1,3,5-triisopropylhexahydro-s-triazine.	do	1-(p-chlorobenzenesulfonyl)-3,5-di(isopropyl)-tetrahydro-s-triazin-2[1H]-one.
40	1,3,5-tri(n-butyl)hexahydro-s-triazine.	do	1-(p-chlorobenzenesulfonyl)-3,5-di(n-butyl)-tetrahydro-s-triazin-2[1H]-one.
41	1,3,5-tri(sec-butyl)hexahydro-s-triazine.	do	1-(p-chlorobenzenesulfonyl)-3,5-di(sec-butyl)-tetrahydro-s-triazin-2[1H]-one.
42	1,3,5-triisobutylhexahydro-s-triazine.	do	1-(p-chlorobenzenesulfonyl)-3,5-di(isobutyl)-tetrahydro-s-triazin-2[1H]-one.
43	N-methylene-t-butyl amine.	do	1-(p-chlorobenzenesulfonyl)-3,5-di(t-butyl)-tetrahydro-s-triazin-2[1H]-one.
44	1,3,5-tris(1-methylbutyl)hexahydro-s-triazine.	do	1-(p-chlorobenzenesulfonyl)-3,5-bis(1-methylbutyl)-tetrahydro-s-triazin-2[1H]-one.
45	1,3,5-tricyclopropylhexahydro-s-triazine.	do	1-(p-chlorobenzenesulfonyl)-3,5-di(cyclopropyl)-tetrahydro-s-triazin-2[1H]-one.
46	1,3,5-tricyclopentylhexahydro-s-triazine.	do	1-(p-chlorobenzenesulfonyl)-3,5-di(cyclopentyl)-tetrahydro-s-triazin-2[1H]-one.
47	1,3,5-tricyclohexylhexahydro-s-triazine.	do	1-(p-chlorobenzenesulfonyl)-3,5-di(cyclohexyl)-tetrahydro-s-triazin-2[1H]-one.
48	1,3,5-tricycloheptylhexahydro-s-triazine.	do	1-(p-chlorobenzenesulfonyl)-3,5-di(cycloheptyl)-tetrahydro-s-triazin-2[1H]-one.
49	N-methylene-2-aminobicyclo[2.2.1]heptane.	do	1-(p-chlorobenzenesulfonyl)-3,5-di(2-bicyclo[2.2.1]heptyl)-tetrahydro-s-triazin-2[1H]-one.
50	N-methylene-2-bicyclo[2.2.2]-octyl amine.	do	1-(p-chlorobenzenesulfonyl)-3,5-di(2-bicyclo[2.2.2]-octyl)-tetrahydro-s-triazin-2[1H]-one.
51	N-methylene-1-adamantyl amine.	do	1-(p-chlorobenzenesulfonyl)-3,5-di(1-adamantyl)-tetrahydro-s-triazin-2[1H]-one.
52	1,3,5-tri(n-butyl)hexahydro-s-triazine.	p-bromobenzenesulfonyl isocyanate.	1-(p-bromobenzenesulfonyl)-3,5-di(n-butyl)-tetrahydro-s-triazin-2[1H]-one.
53	1,3,5-triisobutylhexahydro-s-triazine.	do	1-(p-bromobenzenesulfonyl)-3,5-di(isobutyl)-tetrahydro-s-triazin-2[1H]-one.
54	N-methylene-t-butyl amine.	do	1-(p-bromobenzenesulfonyl)-3,5-di(t-butyl)-tetrahydro-s-triazin-2[1H]-one.
55	1,3,5-tricyclohexylhexahydro-s-triazine.	do	1-(p-bromobenzenesulfonyl)-3,5-di(cyclohexyl)-tetrahydro-s-triazin-2[1H]-one.
56	1,3,5-tricycloheptylhexahydro-s-triazine.	do	1-(p-bromobenzenesulfonyl)-3,5-di(cycloheptyl)-tetrahydro-s-triazin-2[1H]-one.
57	1,3,5-tri(n-propyl)hexahydro-s-triazine.	p-Acetylbenzenesulfonyl isocyanate	1-(p-acetylbenzenesulfonyl)-3,5-di(n-propyl)-tetrahydro-s-triazin-2[1H]-one.
58	1,3,5-tri(n-butyl)hexahydro-s-triazine.	do	1-(p-acetylbenzenesulfonyl)-3,5-di(n-butyl)-tetrahydro-s-triazin-2[1H]-one.
59	1,3,5-tri(sec-butyl)hexahydro-s-triazine.	do	1-(p-acetylbenzenesulfonyl)-3,5-di(sec-butyl)-tetrahydro-s-triazin-2[1H]-one.
60	1,3,5-tri(t-butyl)hexahydro-s-triazine.	do	1-(p-acetylbenzenesulfonyl)-3,5-di(t-butyl)-tetrahydro-s-triazin-2[1H]-one.
61	1,3,5-tricyclopentylhexahydro-s-triazine.	do	1-(p-acetylbenzenesulfonyl)-3,5-di(cyclopentyl)-tetrahydro-s-triazin-2[1H]-one.
62	1,3,5-tricyclohexylhexahydro-s-triazine.	do	1-(p-acetylbenzenesulfonyl)-3,5-di(cyclohexyl)-tetrahydro-s-triazin-2[1H]-one.
63	1,3,5-tricycloheptylhexahydro-s-triazine.	do	1-(p-acetylbenzenesulfonyl)-3,5-di(cycloheptyl)-tetrahydro-s-triazin-2[1H]-one.
64	1,3,5-tris(2-methoxycyclohexyl)-hexahydro-s-triazine.	do	1-(p-acetylbenzenesulfonyl)-3,5-bis(2-methoxycyclohexyl)-tetrahydro-s-triazin-2[1H]-one.
65	N-methylene-1-adamantyl amine.	do	1-(p-acetylbenzenesulfonyl)-3,5-di(1-adamantyl)-tetrahydro-s-triazin-2[1H]-one.
66	1,3,5-tricyclopentylhexahydro-s-triazine.	p-Propionylbenzenesulfonyl isocyanate.	1-(p-propionylbenzenesulfonyl)-3,5-dicyclopentyl-tetrahydro-s-triazin-2[1H]-one.
67	1,3,5-tricyclohexylhexahydro-s-triazine.	do	1-(p-propionylbenzenesulfonyl)-3,5-dicyclohexyl-tetrahydro-s-triazin-2[1H]-one.
68	do	p-Butyrylbenzenesulfonyl isocyanate.	1-(p-butyrylbenzenesulfonyl)-3,5-dibutylhexyl-tetrahydro-s-triazin-2[1H]-one.

Example	Hexahydro-s-triazine or N-methylene amine	Sulfonyl isocyanate	Tetrahydro-s-triazin-2[1H]-one
69	1,3,5-tri(n-propyl)hexahydro-s-triazine.	p-trifluoromethyl-benzene-sulfonyl isocyanate.	1-(p-trifluoromethylbenzenesulfonyl)-3,5-di(n-propyl)tetrahydro-s-triazin-2[1H]-one.
70	1,3,5-tricyclohexylhexahydro-s-triazine.	do	1-(p-trifluoromethylbenzenesulfonyl)-3,5-dicycloheptyltetrahydro-s-triazin-2[1H]-one.
71	1,3,5-tricycloheptylhexahydro-s-triazine.	do	1-(p-trifluoromethylbenzenesulfonyl)-3,5-dicycloheptyltetrahydro-s-triazin-2[1H]-one.
72	1,3,5-tri(n-butyl)hexahydro-s-triazine.	p-methylmercapto-benzene-sulfonyl isocyanate.	1-(p-methylmercaptobenzenesulfonyl)-3,5-di(n-butyl)tetrahydro-s-triazin-2[1H]-one.
73	1,3,5-tricyclohexylhexahydro-s-triazine.	do	1-(p-methylmercaptobenzenesulfonyl)-3,5-dicyclohexyltetrahydro-s-triazin-2[1H]-one.
74	do	p-Ethylmercapto-benzene-sulfonyl isocyanate.	1-(p-ethylmercaptobenzenesulfonyl)-3,5-dicyclohexyltetrahydro-s-triazin-2[1H]-one.
75	do	p-(Isopropylthio)-benzenesulfonyl isocyanate.	1-[p-(isopropylthio)benzenesulfonyl]-3,5-dicyclohexyltetrahydro-s-triazin-2[1H]-one.
76	do	p-(n-Butylthio)-benzenesulfonyl isocyanate.	1-[p-(n-butylthio)benzenesulfonyl]-3,5-dicyclohexyltetrahydro-s-triazin-2[1H]-one.
77	1,3,5-tri(n-butyl)hexahydro-s-triazine.	p-Methoxybenzenesulfonyl isocyanate.	1-(p-methoxybenzenesulfonyl)-3,5-di(n-butyl)tetrahydro-s-triazin-2[1H]-one.
78	1,3,5-tricyclohexylhexahydro-s-triazine.	do	1-(p-methoxybenzenesulfonyl)-3,5-dicyclohexyltetrahydro-s-triazin-2[1H]-one.
79	do	p-(n-Butoxy)benzene-sulfonyl isocyanate.	1-[p-(n-butoxy)benzenesulfonyl]-3,5-dicyclohexyltetrahydro-s-triazin-2[1H]-one.
80	do	p-Fluorobenzenesulfonyl isocyanate.	1-(p-fluorobenzenesulfonyl)-3,5-di-cyclohexyltetrahydro-s-triazin-2[1H]-one.
81	1,3,5-tri(n-butyl)hexahydro-s-triazine.	do	1-(p-fluorobenzenesulfonyl)-3,5-di(n-butyl)tetrahydro-s-triazin-2[1H]-one.
82	1-(methyleneamino)pyrrolidine.	p-Toluenesulfonyl isocyanate.	1-(p-toluenesulfonyl)-3,5-di(pyrrolidinyl)tetrahydro-s-triazin-2[1H]-one.
83	1-(methyleneamino)piperidine.	do	1-(p-toluenesulfonyl)-3,5-dipiperidino-tetrahydro-s-triazin-2[1H]-one.
84	do	p-Chlorobenzenesulfonyl isocyanate.	1-(p-chlorobenzenesulfonyl)-3,5-dipiperidino-tetrahydro-2-triazin-2[1H]-one.
85	do	p-Acetylbenzenesulfonyl isocyanate.	1-(p-acetylbenzenesulfonyl)-3,5-dipiperidino-tetrahydro-s-triazin-2[1H]-one.
86	1-(methyleneamino)-4,4-dimethylpiperidine.	p-Toluenesulfonyl isocyanate.	1-(p-toluenesulfonyl)-3,5-bis(4,4-dimethylpiperidino)tetrahydro-s-triazin-2[1H]-one.
87	1-(methyleneamino)hexahydroazepine.	do	1-(p-toluenesulfonyl)-3,5-bis(4,4-dimethylpiperidino)tetrahydro-s-triazin-2[1H]-one.
88	1,3,5-tris(4-ethoxyethylhexahydro-s-triazine).	do	1-(p-toluenesulfonyl)-3,5-bis(4-ethoxyethylhexyl)tetrahydro-s-triazin-2[1H]-one.
89	1,3,5-tris(2-ethoxycyclohexylhexahydro-s-triazine).	do	1-(p-toluenesulfonyl)-3,5-bis(2-ethoxycyclohexyl)tetrahydro-s-triazin-2[1H]-one.
90	1,3,5-tris(2-methoxycyclohexylhexahydro-s-triazine).	do	1-(p-toluenesulfonyl)-3,5-bis(2-methoxycyclohexyl)tetrahydro-s-triazin-2[1H]-one.

EXAMPLE 91

Preparation of 1-(p-toluenesulfonyl)-3,5-di-(n-butyl)tetrahydro-s-triazin-2[1H]-one—second method

A mixture of 27 parts by weight of 1-(p-toluenesulfonyl)-3-(n-butyl)urea, 7.3 parts by weight of paraformaldehyde, 50 parts by weight of p-dioxane, 0.2 parts by weight of p-toluenesulfonic acid monohydrate, and 174 parts by weight of benzene are heated to reflux under a Dean-Stark trap and maintained at that temperature until water is no longer evolved. The solution is cooled to 15° C. and washed with 2 N hydrochloric acid and saturated aqueous sodium bicarbonate. After drying with anhydrous magnesium sulfate, the solvents are removed by stripping under reduced pressure. The residue is recrystallized to give essentially pure 1-(p-toluenesulfonyl)-3,5-di-(n-butyl)tetrahydro-s-triazin-2[1H]-one.

All of the compounds named in Examples 2-90 can be also prepared according to this procedure by substituting the appropriate urea for 1-(p-toluenesulfonyl)-3-(n-butyl)urea employed above. In addition, the following tetrahydro-s-triazin-2[1H]-ones of this invention can be prepared according to this procedure by substituting the following urea reagents for 1-(p-toluenesulfonyl)-3-(n-butyl)-urea employed above.

fonyl)-3-(n-butyl)urea, 50 parts by weight of p-dioxane, 174 parts by weight of benzene and 7.3 parts by weight of n-butylamine are stirred at room temperature. Next, 6.6 parts by weight of paraformaldehyde and 0.3 part by weight of p-toluenesulfonic acid monohydrate are added and the mixture is refluxed under a Dean-Stark trap until water is no longer evolved. The solvents are removed by stripping under reduced pressure and the residue is recrystallized to give essentially pure 1-(p-toluenesulfonyl)-3,5-di-(n-butyl)-tetrahydro-s-triazin-2[1H]-one.

All of the compounds named in Examples 1-97 can also be prepared according to this procedure by substituting the appropriate urea reagent, amine reagent and urea, n-butylamine, and paraformaldehyde respectively employed as reactants above.

EXAMPLE 99

Preparation of 1-(p-toluenesulfonyl)-3-isopropyl-5-cyclohexyltetrahydro-s-triazin-2[1H]-one and 1-(p-toluenesulfonyl)-3-cyclohexyl-5-isopropyltetrahydro-s-triazin-2[1H]-one

A mixture of 12.8 parts by weight of 1-(p-toluenesulfonyl)-3-isopropylurea, 40 parts by weight of p-dioxane,

Example	Sulfonyl urea	Tetrahydro-s-triazin-2[1H]-one
92	1-(p-aminobenzenesulfonyl)-3-(n-butyl)urea	1-(p-aminobenzenesulfonyl)-3,5-di(n-butyl)-tetrahydro-s-triazin-2[1H]-one.
93	1-(p-aminobenzenesulfonyl)-3-cyclohexylurea	1-(p-aminobenzenesulfonyl)-3,5-dicyclohexyl-tetrahydro-s-triazin-2[1H]-one.
94	1-(4-methyl-3-aminobenzenesulfonyl)-3-cyclohexylurea.	1-(4-methyl-3-aminobenzenesulfonyl)-3,5-dicyclohexyltetrahydro-s-triazin-2[1H]-one.
95	1-(4-methyl-3-aminobenzenesulfonyl)-3-cycloheptylurea.	1-(4-methyl-3-aminobenzenesulfonyl)-3,5-dicycloheptyltetrahydro-s-triazin-2[1H]-one.
96	1-[4-(n-butyl)-3-aminobenzenesulfonyl]-3-cyclohexylurea.	1-[4-(n-butyl)-3-aminobenzenesulfonyl]-3,5-dicyclohexyltetrahydro-s-triazin-2[1H]-one.
97	1-(3,4-dimethylbenzenesulfonyl)-3-cyclohexylurea.	1-(3,4-dimethylbenzenesulfonyl)-3,5-dicyclohexyltetrahydro-s-triazin-2[1H]-one.

EXAMPLE 98

Preparation of 1-(p-toluenesulfonyl)-3,5-di-(n-butyl)-tetrahydro-s-triazin-2[1H]-one—third method

A mixture of 27 parts by weight of 1-(p-toluenesul-

57 parts by weight of benzene and 50 parts by weight of cyclohexylamine are stirred at room temperature. Next, 3.3 parts by weight of paraformaldehyde and 0.3 part by

weight of p-toluenesulfonic acid are added and the mixture is treated as described in Example 98. The crude syrupy residue contains the following four compounds in approximately equal amounts; 1-(p-toluenesulfonyl)-3,5-diisopropyltetrahydro-s-triazin-2[1H]-one, 1-(p-toluenesulfonyl)-3,5-dicyclohexyltetrahydro-s-triazin-2[1H]-one, 1-(p-toluenesulfonyl)-3-isopropyl-5-cyclohexyltetrahydro-s-triazin-2[1H]-one and 1-(p-toluenesulfonyl)-3-cyclohexyl-5-isopropyltetrahydro-s-triazin-2[1H]-one. These compounds can be obtained separately by either fractional crystallization or by chromatography of the crude mixture.

The following tetrahydro-s-triazin-2[1H]-ones of this invention can be made similarly by substituting the following sulfonyleurea reagents and amine reagents for 1-(p-toluenesulfonyl)-3-isopropylurea and cyclohexylamine employed as reactants above.

Example	Sulfonylurea	Amine	Tetrahydro-s-triazin-2[1H]-one
100	1-(p-toluenesulfonyl)-3-(n-butyl)-urea.	Cyclohexylamine.....	1-(p-toluenesulfonyl)-3-(n-butyl)-5-cyclohexyltetrahydro-s-triazin-2[1H]-one. 1-(p-toluenesulfonyl)-3-cyclohexyl-5-(n-butyl)-tetrahydro-s-triazin-2[1H]-one.
101	1-(p-chlorobenzenesulfonyl)-3-(n-propyl)-urea.	.....do.....	1-(p-chlorobenzenesulfonyl)-3-(n-propyl)-5-cyclohexyltetrahydro-s-triazin-2[1H]-one. 1-(p-chlorobenzenesulfonyl)-3-cyclohexyl-5-(n-propyl)-tetrahydro-s-triazin-2[1H]-one.
102	1-(p-acetylbenzenesulfonyl)-3-cyclohexylurea.	Cyclopentylamine.....	1-(p-acetylbenzenesulfonyl)-3-cyclohexyl-5-cyclopentyltetrahydro-s-triazin-2[1H]-one. 1-(p-acetylbenzenesulfonyl)-3-cyclopentyl-5-cyclohexyltetrahydro-s-triazin-2[1H]-one.
103	1-(p-toluenesulfonyl)-3-(n-butyl)-urea.	1-adamantylamine.....	1-(p-toluenesulfonyl)-3-(n-butyl)-5-(1-adamantyl)-tetrahydro-s-triazin-2[1H]-one. 1-(p-toluenesulfonyl)-3-(1-adamantyl)-5-(n-butyl)-tetrahydro-s-triazin-2[1H]-one.
104	1-(p-toluenesulfonyl)-3-(n-butyl)-urea.	Ammonia.....	1-(p-toluenesulfonyl)-3-(n-butyl)-tetrahydro-s-triazin-2[1H]-one.

For Examples 100, 101, 102, and 103, as in the case of Example 99, the product of the reaction is a mixture of four tetrahydro-s-triazin-2[1H]-one compounds which 35 can be separated from one another if so desired.

Utility of compounds

The compounds of this invention can be administered orally and will be used in an amount effective to reduce blood sugar level in the recipient. Ordinarily, doses will range from 0.005 to 5 grams per day. Administration can be spread out over several times per day, as with meals, or otherwise, as convenient. The exact dosage within the recited range will depend on the severity of 45 the affliction, on concurrent treatments, on the physiology of the recipient, on other attendant circumstances, and on the nature of the effect desired.

The compounds can be used according to this invention in a composition which comprises the active compound together with an inert non-toxic pharmaceutical carrier. The composition can take the form of tablet, powder, capsule or other dosage forms. The compounds can be admixed with solid diluents and/or tableting adjuvants such a lactose, mannitol, corn starch, magnesium 55 stearate, talc, gelatin, gums, or the like.

Any of the tableting materials used in pharmaceutical and veterinary practices can be employed where there is no incompatibility with either the active compound of the invention or its biological activity.

Compounds of the invention can be put in dosage forms with or without adjuvants. For example, in a preferred aspect of this invention, a compound with or without a further adjuvant can be placed in a conventional pharmaceutical capsule, such as a gelatin capsule, and be administered in that form.

Compositions containing compounds of the invention will include the presence of the active compound in a powder packet, or such composition can be prepared in the form of a suspension in a material in which the active compound is not soluble.

Compositions containing compounds of the invention can be prepared by conventional procedures and can contain, in addition to one or more of the active compounds, and in addition to the inert adjuvant or adjuvants, one or 75

more other metabolically, therapeutically or nutritionally beneficial ingredients.

These compositions will ordinarily contain from about 10 milligrams to about 500 milligrams of a compound of the invention. A preferred composition will contain from about 25 milligrams to about 500 milligrams of such compound. The active compound will normally constitute from about 1% to 95% by weight of the total composition. Ordinarily, since it will be desired to administer the active compound according to this invention in fairly concentrated form, i.e. with only so much pharmaceutical carrier as is necessary or convenient to assist in administration, the active compound will constitute under most circumstances a fairly high proportion of the total composition.

This invention will be further understood by reference to the following additional examples:

EXAMPLE 105

One-hundred (100) milligrams of 1-(p-toluenesulfonyl)-3,5-di-(n-butyl)-tetrahydro-s-triazin-2[1H]-one, 2.5 milligrams of gelatin, 2.5 milligrams of magnesium stearate and 100 milligrams of mannitol are mixed and formed into a tablet by a conventional tableting machine. If desired, the tablet may be surface-coated by conventional procedures.

EXAMPLE 106

The procedure of Example 144 is followed, using 100 milligrams of 1-(p-toluenesulfonyl)-3,5-diisopropyltetrahydro-s-triazin-2[1H]-one in place of the compound of that example. The tablets may be surface-coated if desired.

EXAMPLE 107

The procedure of Example 144 is followed, substituting 100 milligrams of 1-(p-chlorobenzenesulfonyl)-3,3-di-(n-propyl)-tetrahydro-s-triazin-2[1H]-one for the active ingredient of that example. The tablets may be surface-coated if desired.

EXAMPLE 108

A plurality of unit capsules is prepared by filling standard two-piece hard gelatin capsules weighing about 50 milligrams each (#3) with 100 milligrams of powdered 1-(p-toluenesulfonyl)-3,5-di-(n-hexyl)-tetrahydro-s-triazin-2[1H]-one.

EXAMPLE 109

A plurality of unit capsules is prepared by filling standard two-piece hard gelatin capsules (#3 size) with 100 milligrams of powdered 1-(p-chlorobenzenesulfonyl)-3,5-diisopropyltetrahydro-s-triazin-2[1H]-one.

EXAMPLE 110

An effective hypoglycemic oral suspension is prepared by admixing 1 part by weight of 1-(p-toluenesulfonyl)-3,5-di-(n-propyl)-tetrahydro-s-triazin-2[1H]-one, 5 parts by weight of Acacia, N.F., 1.5 parts by weight of Cyclamate Sodium, N.F., and 92.5 parts by weight of water.

11

EXAMPLE 111

The procedure of Example 110 is followed, using 1 part by weight of 1-(p-toluenesulfonyl)-3,5-dicyclohexyltetrahydro-s-triazin-2[1H]-one in place of the active ingredient of that example.

The disclosure herein should not be considered a recommendation to utilize the disclosed invention in any way without full compliance with U.S. Food and Drug Laws.

I claim:

1. A compound of the formula:

where:

R₁ is selected from the group consisting of

wherein X is selected from the group consisting of hydrogen, alkyl of 1-4 carbon atoms, alkoxy of 1-4 carbon atoms, alkylthio of 1-4 carbon atoms, alkanoyl of 2-4 carbon atoms, trifluoromethyl, chlorine, fluorine, bromine and amino, and Y is selected from the group consisting of hydrogen and alkyl of 1-4 carbon atoms;

R₂ is selected from the group consisting of alkyl of 2-10 carbon atoms, cycloalkyl of 3-8 ring carbon atoms, cycloalkenyl of 3-8 ring carbon atoms, bicycloalkyl of 7-10 ring carbon atoms, bicycloalkenyl of 7-10 ring carbon atoms, tricycloalkyl of 8-11 ring carbon atoms, tricycloalkenyl of 8-10 ring carbon atoms,

wherein n is 0, 1, or 2;

R₃ is selected from the group consisting of R₂ and hydrogen.

2. A compound of the formula

where:

Z is selected from the group consisting of methyl, acetyl, chlorine and bromine;

R₄ and R₅ are selected from the group consisting of alkyl of 3-6 carbon atoms, cycloalkyl of 5-7 ring carbons, bicycloalkyl and bicycloalkenyl of 7-8 ring carbons and tricycloalkyl of 10 ring carbons.

3. 1-(p-toluenesulfonyl)-3,5-di-(n-butyl)tetrahydro-s-triazin-2[1H]-one.

4. 1-(p-chlorobenzenesulfonyl)-3,5-di-(n-propyl)tetrahydro-s-triazin-2[1H]-one.

5. 1-(p-toluenesulfonyl)-3,5-dicyclohexyltetrahydro-s-triazin-2[1H]-one.

6. 1-(p-toluenesulfonyl)-3,5-di(1-adamantyl)tetrahydro-s-triazin-2[1H]-one.

7. 1-(p-chlorobenzenesulfonyl)-3,5-di(1-adamantyl)tetrahydro-s-triazin-2[1H]-one.

8. 1-(p-toluenesulfonyl)-3,5-dipiperidinotetrahydro-s-triazin-2[1H]-one.

9. 1-(p-toluenesulfonyl)-3,5-dicycloheptyltetrahydro-s-triazin-2[1H]-one.

12

10. 1-(p-toluenesulfonyl)-3,5-di(n-propyl)tetrahydro-s-triazin-2[1H]-one.

11. A process for the preparation of a compound of the formula:

where:

R₁ is selected from the group consisting of

wherein X is selected from the group consisting of hydrogen, alkyl of 1-4 carbon atoms, alkoxy of 1-4 carbon atoms, alkylthio of 1-4 carbon atoms, alkanoyl of 2-4 carbon atoms, trifluoromethyl, chlorine, fluorine and bromine, and Y is selected from the group consisting of hydrogen and alkyl of 1-4 carbon atoms;

R₂ is selected from the group consisting of alkyl of 2-10 carbon atoms, cycloalkyl of 3-8 ring carbon atoms, cycloalkenyl of 3-8 ring carbon atoms, bicycloalkyl of 7-10 ring carbon atoms, bicycloalkenyl of 7-10 ring carbon atoms, tricycloalkyl of 8-11 ring carbon atoms, tricycloalkenyl of 8-10 ring carbon atoms,

wherein n is 0, 1, or 2;

comprising reacting at a temperature in the range of from 10° to 100° C., an aryl sulfonyl isocyanate of the formula

40 where R₁ is as defined above with a substituted methylene amine selected from the group consisting of

(a) R₂-N=CH₂ and (b)

50 where R₂ is as defined above in a molar ratio of said aryl sulfonyl isocyanate to said methylene amine of 1:2 in case of the amine being Formula a above and 1:3/2 in the case of the amine being Formula b above.

55 12. A process for the preparation of a compound of the formula:

where:

R₁ is selected from the group consisting of

wherein X is selected from the group consisting of hydrogen, alkyl of 1-4 carbon atoms, alkoxy of 1-4 carbon atoms, alkylthio of 1-4 carbon atoms, alkanoyl of 2-4 carbon atoms, trifluoromethyl, chlorine, fluorine and bromine, and Y is selected from the group consisting of hydrogen and alkyl of 1-4 carbon atoms,

13

R_2 is selected from the group consisting of alkyl of 2-10 carbon atoms, cycloalkyl of 3-8 ring carbon atoms, cycloalkenyl of 3-8 ring carbon atoms, bicycloalkyl of 7-10 ring carbon atoms, bicycloalkenyl of 7-10 ring carbon atoms, tricycloalkyl of 8-11 ring carbon atoms, tricycloalkenyl of 8-10 ring carbon atoms,

wherein n is 0, 1, or 2;
comprising reacting a substituted sulfonyl urea of the formula

where R_1 and R_2 are defined as above in solution of an

5

10

15

14

inert anhydrous solvent with a source of formaldehyde at a temperature in the range of from 20° to 150° C. and removing from the reaction the water of reaction formed.
